UNITED STATES PATENT OFFICE

152,580

DESIGN FOR A PORTABLE BEVERAGE
COOLER

Grant M. Acton, Arkansas City, Kans., assignor
to Acton Manufacturing Company, Inc., a cor-
poration of Kansas

Application August 6, 1947, Serial No. 140,714

Term of patent 14 years

(Cl. D67—4)

To all whom it may concern:

Be it known that I, Grant M. Acton, a citizen of the United States, residing at Arkansas City, in the county of Cowley and State of Kansas, have invented a new, original, and ornamental Design for Portable Beverage Cooler, of which the following is the specification, reference being had to the accompanying drawing, forming part thereof.

Fig. 1 is a perspective view of a portable beverage cooler showing my new design, and particularly illustrating the front and top thereof.

Fig. 2 is an end elevational view thereof.

Fig. 3 is a plan view thereof.

Fig. 4 is a rear elevational view thereof.

This application is a continuation-in-part of my copending application Serial No. D. 123,890, filed November 19, 1945, now abandoned.

I claim:

The ornamental design for a portable beverage cooler, substantially as shown.

GRANT M. ACTON.
